UNITED STATES PATENT OFFICE.

JOSEPH HALLER, OF CHICAGO, ILLINOIS.

BELT-BUCKLE.

1,073,115.

Specification of Letters Patent. Patented Sept. 16, 1913.

Application filed September 11, 1912. Serial No. 719,774.

To all whom it may concern:

Be it known that I, JOSEPH HALLER, a citizen of the United States, residing at Chicago, in the county of Cook and State 5 of Illinois, have invented certain new and useful Improvements in Belt-Buckles, of which the following is a specification.

The buckle which is the subject of the present invention is designed more particularly for use in connection with belts employed for supporting trousers, and it is the object of the invention to provide a buckle of this kind having novel and improved means whereby the front portion of 15 the trousers is held up and prevented from sagging or protruding below the belt.

With this object in view, the invention consists in a combination and arrangement of parts to be hereinafter described and 20 claimed, reference being had to the accompanying drawing in which—

Figure 1 is a plan view of the buckle and a fragment of the belt to which the buckle is applied. Fig. 2 is a view similar 25 to the preceding showing the reverse side. Fig. 3 is a longitudinal section on the line 3—3 of Fig. 1. Fig. 4 is an edge view showing the mode of attaching the buckle to the trousers.

Referring specifically to the drawing, the buckle comprises spaced side bars 5 connected at their ends by cross-bars 6 and 7, respectively. The side bars have an up-standing marginal flange 8 in which is 30 journaled a transverse pin 9 from one side of which, and at a right angle thereto, extends a tongue 10. From the opposite side of the pin extends a hook 12 having its bill offset from the pin upward and toward 35 the cross-bar 7, and extending parallel to said pin and cross-bar, as clearly shown in Fig. 2. The bill of the hook lies above the cross-bar 7 and is spaced therefrom.

The buckle herein described is permanently fastened to one end 13 of the belt by passing the same around the pin 9 and sewing the end to the main portion of the belt close to the cross-bar 7, as indicated at 40 45 50

bar 7. The other end of the belt has eyelets 15 and is passed over the cross-bar 6 and into the space between the side bars 5. The tongue 10 passes through an aperture in the looped portion of the first mentioned 55 end of the belt and projects therefrom and toward the cross-bar 6, and said tongue is adapted to be passed through a selected one of the eyelets 15 for securing the belt in adjusted position.

The trousers 16 have the usual hook 17 and eye 18 at the waist-band for closing the same. When the belt is placed in position around the waist-band and buckled up, the hook 12 is slipped into the hook 17 65 whereby the belt and trousers are coupled together, and the latter is prevented from sagging or working down below the belt.

A buckle constructed as herein described is devoid of complicated parts, it can be 70 cheaply manufactured, and it effectually serves the purpose for which it is designed.

I claim:

1. A buckle comprising side-bars and cross-bars connecting the same, a transverse 75 pin journaled by the side-bars, a penetrating tongue projecting from one side of the pin, toward one of the cross-bars, and a hook projecting from the opposite side of the pin and having its bill extending transversely of the buckle and lying above the other cross-bar, the extremity of the bill being spaced from the pin, the tongue and hook being fixed to the transverse pin.

2. A buckle comprising side bars and 80 cross-bars connecting the same, a transverse pin journaled in the side bars, an integral penetrating tongue projecting from one side of the pin toward one of the cross-bars, and an integral hook projecting from the 90 opposite side of the pin and having its bill extending transversely of the buckle and lying above the other cross-bar.

In testimony whereof I affix my signature in presence of two witnesses.

JOSEPH HALLER.
